(57) **CLAIM**

The ornamental design for an adjustable wrench, as shown and described.

DESCRIPTION

FIG. 1 is a perspective view of my design for an adjustable wrench;

FIG. 2 is a front elevational view thereof;

FIG. 3 is a right side view thereof;

FIG. 4 is a left side view thereof;

FIG. 5 is a top view thereof;

FIG. 6 is a bottom view thereof; and,

FIG. 7 is an alternate perspective view thereof; showing the movable jaw in an open position.

The broken lines shown in the drawings show unclaimed subject matter only and form no part of the claimed design.
